UNITED STATES PATENT OFFICE.

CHARLES A. ALEXANDERSON, OF NEW YORK, N. Y., ASSIGNOR TO EMMA W. D. HUMPHREY, HELEN W. D. MILEHAM, AND GUARANTY TRUST COMPANY, ADMINISTRATORS OF EUGENE W. DURKEE, DECEASED.

APPARATUS FOR COVERING THE OPENINGS IN PERFORATED COVERS FOR CONTAINERS WITH PAPER OR LIKE MATERIAL.

Application filed August 18, 1927. Serial No. 213,963.

My invention relates to covers for cans and other containers for holding ground or powdered material in which the covers are perforated for sifting the material when desired, and the principal object of my invention is to provide mechanical means for temporarily covering the perforations in the covers, for transportation or when not in use.

It is very common in containers for ground or powdered substances, to provide perforated covers for sifting the contents when desired, such perforations being normally closed by a disk provided with corresponding perforations which may be rotated to bring such perforations into register with the perforations in the cover proper, but such construction is expensive, and to lessen such expense I am aware that while it is not a common practice, in some instances a strip of paper has been pasted over the perforations in the covers, which can be easily punctured to allow the contents of the containers to be sifted. To the best of my knowledge and belief, however, these papers have been applied to the covers by hand which is a slow and expensive practice. My invention provides an apparatus for applying such paper covering over the perforations in the container covers and consists in means for conveying the covers to position, means for applying adhesive to the surface of the covers, means for shifting the covers to position to receive the paper upon their glued surfaces, means for feeding the paper from rolls, means for picking up the forward ends of the fed paper by suction, means for shutting off the suction, means for cutting off strips of the picked up paper into the required size to fit into or upon the covers, means for pressing such cut off strips of paper upon the glued surfaces of the covers, and means for carrying the covers to a proper receptacle after the paper has been so applied. The details of the construction and operation of my new apparatus are hereinafter particularly described.

In the accompanying drawings—

Figure 1 is a top plan view of a machine embodying my invention.

Fig. 2 is a front elevation of the same.

Fig. 3 is a section on the broken line 3—3 of Fig. 1.

Fig. 4 is a plan view similar to Fig. 1 with parts broken away for clearness. 55

Fig. 5 is a section on the broken line 5—5 of Fig. 1.

Fig. 6 is a detail view showing cover ready to be moved from the machine.

Fig. 7 is a similar view showing cover moved from the position shown in Fig. 6. 60

Fig. 8 is a section on the broken line 8—8 of Fig. 7.

Fig. 9 is a section on the broken line 9—9 of Fig. 4. 65

Fig. 10 is a section on the broken line 10—10 of Fig. 9.

Fig. 11 is a section on the broken line 11—11 of Fig. 2.

Fig. 12 is a section on the broken line 70 12—12 of Fig. 11.

Fig. 13 is a section on the broken line 13—13 of Fig. 11.

Fig. 14 is a section on the broken line 75 14—14 of Fig. 11.

Fig. 15 is an inverted plan view of one of the covers as fed to the machine.

Fig. 16 is a similar view after the adhesive has been applied.

Fig. 17 is a similar view after the paper 80 covering the perforations has been applied, and

Fig. 18 is a longitudinal section of the same.

Referring to the drawing, 10 denotes the 85 bed of the machine supported on vertical posts 11 the lower ends rest upon and are secured to a solid base 13 which is supported by standards 12 as shown.

The bed or table 10 is supported at a 90 height convenient to the operator.

The main drive shaft 14 is mounted and supported in brackets 15, bolted or otherwise secured to the base 13 and is driven by the motor 17, a belt 18, passing over a 95 pulley 19, on the motor shaft 20, and over a pulley 21, secured to the drive shaft 14. The connection between the motor and drive shaft is controlled by a friction clutch 22 operated by the hand lever 23. The motor is 100 supported by a bracket 24, fixed to the under side of the bed 10 or in any other suitable manner.

Three equally spaced parallel arms or branches 25, 26 and 27, extend horizontally 105 from the bed 10 to which they may be se-

cured in any suitable manner but are preferably made integral therewith. These arms have flat vertical sides and adjacent their outer ends are provided with aligned holes for the passage of a pin 28, there being a roller 29 loosely mounted upon this pin between the arms 25 and 26 and another roller 30, being mounted in like manner between the arms 26 and 27. A conveyor belt 31 for the covers 16, passes over the roller 30 and through a slot in the bed 10, over another roller 32 fixed to a shaft 33 mounted in bearings below the bed. A shaft 48 is driven by a bevel gear 34 meshing with a bevel gear 35, driven by a chain belt 36, passing over a sprocket wheel 37 and another sprocket wheel 38 mounted on a shaft 39 upon which is fixed a large gear wheel 40, meshing with a pinion 41, fixed to a shaft 42 mounted in bearings 43 on the frame.

Fixed to the shaft 42, is a large gear wheel 44, meshing with a pinion 45, fixed to the main drive shaft 14. A return belt 46 passes over the roller 29 and through the slot in the bed over a roller 47 fixed to the shaft 48 mounted in bearings below the bed which shaft 33 is rotated in the opposite direction to the shaft 48 by a gear 49 upon the shaft 48 engaging a gear 50 upon the shaft 33. In the top of the bed 10, there is a recess or groove of a width corresponding to the space between the arms 25 and 27 and of a depth so that the top of the belts 31 and 46 come flush with the bottom of such recess, the sides of the arms 25, 26 and 27 extending higher than the tops of the belts, forming guides for the covers 16, which are placed upon the conveyor belt 31 by the operator at the forward end of the belt. 60 denotes a disk provided with a central hub 61, having a hole through its center. To this hub on each side of the disk 60 is secured disks 62 and 63, respectively, each provided with a hole in alignment with the hole in the hub 61. These disks are loosely mounted on a pin 64 which passes through these holes and is supported in bearing in upright brackets 65 and 66 secured at their base to the top of the bed 10 by bolts 67, or in any other suitable way. The pin 64 is preferably provided with a knurled head 68 at one end.

A roll of paper 70 is mounted upon the hub 61 between the disks 60 and 62, and another roll of paper 71 is mounted upon the hub 61 between the disks 60 and 63. A guide roller 72 is loosely mounted upon a pin 73 supported in bearings in upright brackets 74 and 75, secured to the top of the bed 10 at their base by bolts or screws.

This roller 72 is reduced in diameter at each side of its central portion, with a disk 76 fixed to the end of each reduced part, which parts are in alignment with the rolls of paper, the paper passing under the reduced parts of the roller 72 as it is drawn

from the rolls 70 and 71 by rubber rollers 78 and 79 fixed to shafts 80 and 81, which shafts are mounted in bearings in brackets 82 and 83 fixed to the top of the bed 10 by screws or bolts.

A gear 84 is mounted upon the shaft 80 upon which is a ratchet wheel 85. This wheel 85 is operated by a pawl 86, pivotally connected to an arm 87 by screws 88. At the end of the arm 87 is attached a roller 89 which works in a groove 90 in a cam wheel 91, driven from the shaft 39.

A shaft 100 is supported in bearings in brackets 101 fixed to the top of the bed 10 in any suitable manner, around which is coiled a spring 102, in alignment with each roll of paper. The upper projecting ends of these springs bear against spring fingers 103, fixed at one end to the top of the brackets 101, and extending beneath and bearing against each roll of paper to steady the rolls and prevent buckling as the paper is drawn off.

The paper as it passes from between the rubber rollers 78 and 79 is received upon a plate 104 supported upon the bed 10, which plate has a down-turned end 105, which forms a cutting edge and as the paper reaches this point it is cut off by a knife 106 into lengths of a size to fit into or upon the covers 16. This knife is pivotally connected by a pin 107 supported in upright brackets 108, fixed to the top of the bed 10 to an arm 110, being pivotally connected with a block 111, screwed upon the upper end of a vertical rod 112, which passes through a hole in the bed 10. A nut 113 is screwed upon this rod 112 up against the lower end of the block 111 and surrounding the rod between this nut and the top of the bed is a spiral spring 114. The lower end of the rod 112, extending beneath the bed, is screwed into the upper end of arm 115 and secured by a nut 116. This arm 115 is mounted upon a shaft 117 which is supported in bearings upon brackets 118 bolted to the under side of the bed 10.

On the shaft 117 is mounted a sprocket 119, driven by a chain 120 passing over a sprocket 121 fixed to the shaft 39. 122 denotes a flat vertical shaft which passes through an opening in the bed 10 and extends a predetermined distance above the bed. The lower end of this flat shaft fits slidably into a slot 123 in an upright bracket 124, fixed to the base 13. Attached to the shaft 122, at or about its center, is a rod 125 having a hub 126, pivotally mounted on a bolt 127, which passes through a hole in the shaft and is secured by a lock nut 128. The lower end of the rod 125 is threaded which end is screwed into an arm 129 and secured by a lock nut 130. Adjacent the lower end of the arm 129, there is attached a roll 131, which fits into a groove 132 in a

cam wheel 133 mounted upon the shaft 39.

It will thus be seen that while the machine is being operated, the flat shaft 122 is given an up-and-down movement. Fixed to the upper end of the shaft 122, by screws or bolts, is a bracket 134, having two spaced horizontal branches 135 and 136, which extend over the recess in the top of the bed a predetermined distance and at a predetermined height above the bed. Fixed into the lower end of the branch 135, there are two spaced pads or blocks 137 of soft material, preferably sponge rubber, and similar pads 138 are fixed into the lower end of the branch 136. As the paper passes off the edge of the plate 104 it is drawn by suction up against the bottoms of the pads 137 in the branch 135, and is immediately cut off by the knife 106 which at that moment is operated.

To accomplish this, I provide two spaced suction tubes 141 and 142, joined together by coupling nuts 143 and 144. These tubes extend through openings in the top of the branch 135, their lower ends being reduced in diameter and extending through the pads 137, nearly flush with the bottom surface thereof.

The tubular end of the coupling nut 144 passes into one end of a flexible tube 145, the other end of which passes over the upper end of a metal tube 146, supported at 147, upon the back of the flat shaft 122. To the lower end of the tube 146 is connected another section of flexible tubing 148, the other end of which connects with the upper end of another vertical metallic tube 149, the lower end of which is screwed into the top of a valve chamber 150, which is connected at its lower end by a tube 151, with a pump 152. This pump is operated by a belt 153, which passes over a pulley 154 fixed to the pump shaft 155 and over another pulley 156, fixed to the drive shaft 14. The valve in the chamber 150 may be opened or closed by a cock 157, but ordinarily the suction is regulated automatically by the valve 150 coupled in the line of tubing supported by a bracket 158, attached by screws or bolts 159, to the under side of the bed 10.

A collar 160 surrounds the lower end of the valve casing which collar is provided with a down-turned arm 161 to which is pivoted one end of a link 162, having a projection or finger 163, upon which the lower end of the valve stem 164 is seated. A roll 165 is pivotally secured to the free end of the link 162 which roll is acted upon by a cam 166 fixed upon the shaft 117. It will thus be seen that when the cam 166 contacts with the roll 165, the end of the link 162 is depressed whereby the finger 163, on the other end of the link 162, is raised pressing the valve stem 164 upward opening the

valve, thus allowing for the suction in the tubes 141, 142.

The coupling nut 144 is provided with a hole 167 for breaking any vacuum remaining in the tubing between it and the valve 150, after such valve has been closed.

A tank 168 for holding glue or other adhesive is seated upon the bed 10 and held in position by a bolt 169, which passes through a hole in the bed with a lock nut 170, upon its lower end beneath the bed, said bolt being provided with a flange 171, which rests upon the top of the bed, the upper end of the bolt being threaded and passing through a hole in an angle piece 172, secured to the rear end of the tank 168, there being a thumb nut 173 screwed upon the upper threaded end of the bolt, by the removal of which the tank may be lifted off the bed for cleaning or other purposes.

A glue roller 174 is positioned within the tank 168, upon a shaft 175, mounted in bearings in the tank. Upon one end of the glue shaft 175 is fixed a gear 176, meshing with a gear 177 on a shaft 178 upon which is also fixed the sprocket wheel 37, driven by the chain 36, passing over the sprocket wheel 38 on the shaft 39.

Two spaced parallel arms 182 and 183 are supported a predetermined distance above the bed 10 by brackets 184. The facing sides of the arms 182 and 183 are provided with longitudinal slots through which slide ribs 186 and 187 fixed to a frame 188, in the forward end of which is journalled a shaft 189 upon which is fixed two rubber rolls 190 and 191 which normally are in contact with the glue roller 174 by which they are coated with the glue or other adhesive material. The rear end of the frame 188 is bent at right angles to the central part where it is again bent at right angles forming a slot 192, into which extends the upper end of a lever 193, pivotally connected in the slot 192 by a bolt 194 to the frame 188. This lever 193 is fulcrumed to a lug 195 fixed to the upright 11 of the frame by a bolt 196.

The lower end of the lever 193 is pivotally connected by a bolt 197 to one end of a rod 198, the other end of such rod being reduced in diameter and threaded, which end is connected with a forked member 199, which straddles the shaft 39, upon which is mounted a cam wheel 200, there being a roll 201 attached to the forked member 199 which works in the cam slot 202 in the cam wheel 200.

While the machine is in operation, the frame 188 is continuously carried forward and backward over the bed whereby the rubber rolls 190 and 191 to which the glue or other adhesive has been applied by the glue roller 174 are carried under and in contact with the under surface of the pads

138, applying the adhesive thereto. The movements of the parts are so timed that just as the rubber rolls 190 and 191 pass off the pads 138 with the backward movement of the frame 188, the shaft 122 descends by means of the mechanism hereinbefore described, and when said shaft reaches its lowermost position, the pads 138 come into contact with two of the covers which have at that time come into position under and in alignment with said pads whereby the surface of each of said covers receives a coating of the adhesive carried by such pads. A push plate 203 attached to the frame 188 projects a predetermined distance beyond the rubber rolls 190 and 191, and as the frame 188 moves forward the two covers which have previously received a coating of the adhesive, are pushed by this plate into position under and in alignment with the pads 137 carried by the suction tubes 141 and 142 and against which the cut off sections of paper have been sucked up, so that upon the next downward movement of the shaft 122, these sections of paper are pressed by the pads 137 against the glued surfaces of the covers to which they adhere, the suction in the tubes 141 and 142 being at that moment cut off by the closing of the valve 150, through the means heretofore described.

Secured to the underside of the bed 10, directly under the recess therein and in line with the return belt 46, there is a guide frame 204 having a longitudinal tongue 205 at its bottom which enters a longitudinal groove in a sliding rack 205'. Upon one end of this sliding rack is secured a casing 206, having a hole in one end through which passes a pin 207 provided with a head 208 at its upper end and with a knob 209 at its lower end. A plug 210 is fixed in the outer end of the casing with another plug 211, concave on one side to conform to the surface of the pin 207 in the other end of the casing and in contact with the pin, between which plugs there is a spiral spring 212 so that the pin is not rigidly held.

There is an elongated slot in the bed 10 through which the head of the pin may pass.

A vertical rack 213 is secured to the shaft 122 so that it moves upward and downward with such shaft.

A gear wheel 214 is loosely mounted upon a fixed shaft 215, and secured to the gear wheel 214 is a small gear 216, which meshes with the vertical rack 213, the gear wheel 214 meshing with the sliding rack 205'. It will thus be seen that upon the upward and downward movements of the shaft 122, the rack 205' will be moved horizontally beneath the bed 10, first in one direction and then the other. At one end of the frame 204 is secured an inclined cam 217 and at the other end of the frame is secured another inclined cam 218.

Upon the backward movement of the rack 205', the knob 209 on the lower end of the pin 207 rides over the top of the cam 217, so that the head 208 of the pin is pushed up through the slot in the bed directly behind the covers which are at that time under the pads 137, having received the strips of paper upon their glued surfaces by the previous downward movement of the shaft 122. This position of the pin 207 is best illustrated in Fig. 6. Upon the forward movement of the rack 205', the head of the pin 207 pushes the covers which have been thus treated off upon the delivery belt 46 by which they are carried until they fall into any suitable receptacle provided for that purpose. As the head of the pin 207 pushes the covers onto the delivery belt 46, the pin is drawn down by the knob 209 on its lower end passing under the guide 218. This is best illustrated in Figs. 5 and 7 of the drawings.

I provide a hand wheel 219 by which the shaft 42 may be rotated, should occasion require. It being preferable that the paper be applied to the under surface of the covers, I have illustrated the covers in an inverted position, but it will be apparent that the paper can be applied in the same way to the top surface of the covers, if desired.

While only one size and shape of cover is shown, it is obvious that perforated covers of various sizes and shapes may be sealed in like manner, without departing from the spirit and nature of my invention.

I claim as my invention:

1. In an apparatus for covering the openings in perforated covers for containers with paper or like material, the combination of a conveyor for the covers, means for applying adhesive to the surface of the covers, means for supporting a roll or rolls of paper or like material, means for drawing such material from the roll or rolls, means for picking up the forward ends of such material by suction, means for cutting off such picked up portions, means for conveying the covers after receiving the adhesive to a position below and in alignment with the suspended strips of material, means for shutting off the suction, and means for pressing such strips of material upon the surfaces of the covers to which the adhesive has been applied.

2. In an apparatus for covering the openings in perforated covers for containers with paper or like material, the combination of a bed, supports for the same, means for conveying the covers to a position to be acted upon, means for applying adhesive to the covers, means upon the bed for supporting a roll or rolls of paper or like material, means for drawing such material from the rolls, means for picking up the forward ends of such material by suction, means for cutting off such picked up portions, means

for conveying the covers to which the adhesive has been applied to a position below and in alignment with such suspended strips of material, means for shutting off the suction, and means for pressing such strips of material upon the covers.

3. In an apparatus of the character described, the combination of a bed, supports for the same, a conveyor belt for the covers, a delivery belt for the same, means for driving such belts in opposite directions, means for applying adhesive to the covers, means upon the bed for supporting a roll or rolls of paper, means for drawing the paper from the rolls, means for picking up the forward ends of the paper by suction, means for cutting off such picked up ends of the paper into pieces of the desired length, means for conveying the covers to which the adhesive has been applied to a position below and in alignment with such suspended lengths of paper, means for shutting off the suction, means for pressing the lengths of paper upon such covers causing the paper to adhere thereto, and means for pushing such covers on to the delivery belt.

4. In an apparatus for covering the openings in perforated covers for containers with paper or like material, the combination of a bed, supports for the same, means upon the bed for supporting a roll or rolls of paper or like material, means for drawing such material from the rolls, a knife, means for operating the knife to cut off certain lengths of such material, a vertical shaft passing through an opening in the bed, a bracket secured to said shaft above the bed, said bracket having a horizontal branch, spaced suction tubes supported in said branch, spaced pads of sponge rubber or similar material fixed in the bottom of said branch through which the lower ends of the suction tubes extend, connected sections of flexible and metallic tubing extending from the top of the suction tubes for connection with a pump, a valve in said line of tubes, and means for opening and closing such valve intermittently, whereby when the valve is open the cut-off length of paper or like material is sucked up against said pads through which said suction tubes extend, and released therefrom when said valve is closed, a glue tank secured to the top of the bed, a glue roller, a shaft upon which the same is supported in said tank, means for rotating said shaft a horizontal frame, grooved bearings for the same at each side of the glue tank, spaced rubber rolls mounted on a pin supported in the forward end of said frame, said rubber rolls being normally in contact with the glue roller and rotated thereby, means for giving said frame a forward and backward movement whereby on the forward movement of the frame said rubber rolls pass over the under surfaces of said pads in the second branch of the bracket and apply a coating of glue thereto, means for giving said vertical shaft an up and down movement, whereby upon the downward movement of such shaft, a coating of glue is applied upon the surface of the covers and the cut-off lengths of paper or similar material are pressed upon such coated surfaces of the covers.

5. In a machine of the character described, the combination of a bed, supports for the same, a glue tank secured to the top of the bed, a glue roller, a shaft upon which the glue roller is supported in said tank, means for rotating said shaft, a vertical shaft passing through an opening in the bed, a bracket secured to said shaft above the bed, said bracket having a horizontal branch, spaced pads of sponge rubber or similar material fixed in the bottom of said branch, a horizontal frame, grooved bearings for such frame at each side of the glue tank, spaced

rubber rolls mounted on a pin supported in the forward end of said frame, said rubber rolls being normally in contact with the glue roller and rotated thereby, means for giving said frame a forward and backward movement whereby on the forward movement of the frame, said rubber rolls pass over the under surface of said pads in the bracket branch and apply a coating of glue thereon.

6. In an apparatus for covering the openings in perforated covers for containers with paper or similar material, the combination of a bed, supports for the same, means upon the bed for supporting a roll or rolls of paper or like material, means for drawing such material from the rolls, a knife, means for operating the knife to cut off certain lengths of such material, a vertical shaft passing through an opening in the bed, a bracket having two spaced horizontal branches, said bracket being secured to the vertical shaft above the bed, spaced pads of sponge rubber or like material fixed in the bottom of each of said branches, spaced suction tubes supported in one of said branches and passing through said pads in such branch, connected sections of flexible and metallic tubing extending from the top of the suction tubes for connection with a pump, a valve in said line of tubing, means for opening and closing such valve intermittently, whereby when the valve is open the cut-off length of paper or like material are sucked up against said pads through which said suction tubes extend, and released therefrom when said valve is closed, a glue tank secured to the top of the bed, a glue roller, a shaft upon which the same is supported in said tank, means for rotating said shaft a horizontal frame, grooved bearings for the same at each side of the glue tank, spaced rubber rolls mounted on a pin supported in the forward end of said frame, said rubber rolls being normally in contact with the glue roller and rotated thereby, means for giving said frame a forward and backward movement whereby on the forward movement of the frame said rubber rolls pass over the under surfaces of said pads in the second branch of the bracket and apply a coating of glue thereto, means for giving said vertical shaft an up and down movement, whereby upon the downward movement of such shaft, a coating of glue is applied upon the surface of the covers and the cut-off lengths of paper or similar material are pressed upon such coated surfaces of the covers.

7. In an apparatus for covering the openings in perforated covers for containers with paper or like material, the combination of a bed, supports for the same, means upon the bed for supporting a roll or rolls of paper or like material, means for drawing such material from the rolls, a knife, means for operating the knife to cut off certain

lengths of such material, a vertical shaft passing through an opening in the bed, a bracket having two spaced horizontal branches, said bracket being secured to the 5 vertical shaft above the bed, spaced pads of sponge rubber or like material fixed in the bottom of each of said branches, spaced suction tubes supported in one of said branches and passing through said pads in such 10 branch, connected sections of flexible and metallic tubing extending from the top of said suction tubes for connection with a pump, a valve in said line of tubing, means for opening and closing such valve intermittently, whereby when the valve is open the cut-off lengths of paper or like material are sucked up against said pads through which the suction tubes extend, and released therefrom when the valve is closed, a glue 15 tank secured to the top of the bed, a glue roller, a shaft upon which the same is mounted in said tank, means for rotating said shaft, a horizontal frame, grooved bearings for the same at each side of the 20 glue tank, spaced rubber rolls mounted on a pin supported in the forward end of said frame, said rubber rolls being normally in contact with the glue roller and rotated thereby, a push plate attached to said frame 25 below said rubber rolls and projecting beyond them, means for giving said frame a forward and backward movement whereby on the forward movement of the frame said rubber rolls pass over the under surface of 30 said pads in the second branch of said bracket and apply a coating of glue thereto, means for giving said vertical shaft an up and down movement whereby on the downward movement of such shaft a coating of 35 glue is applied upon the surface of the covers by such coated pads, while the covers previously so coated are pushed by said push plate to position below and in alignment with said pads in the other branch of the 40 bracket which press the cut-off lengths of paper or like material upon the glue coated surfaces of the covers.

8. In an apparatus for covering the openings in perforated covers for containers 50 with paper or like material, the combination of a bed, supports for the same, a conveyor belt for the covers, a delivery belt for the same, means for driving such belts in opposite directions, means upon the bed 55 for supporting a roll or rolls of paper or

like material, means for drawing such material from the rolls, a knife, means for operating the knife to cut off certain lengths of such material, a vertical shaft passing through an opening in the bed, a bracket 60 having two spaced horizontal branches, said bracket being secured to the vertical shaft above the bed, spaced pads of sponge rubber or like material fixed in the bottom of each of said branches, spaced suction tubes supported in one of said branches and passing through said pads in such branch, connected sections of flexible and metallic tubing extending from the top of said suction tubes 65 for connection with a pump, a valve in said line of tubing, means for opening and closing such valve intermittently, whereby when the valve is open the cut off lengths of paper or like material are sucked up against said pads through which the suction tubes extend and released therefrom when the valve is closed, a glue tank secured to the top of the bed, a glue roller, a shaft upon which the same is mounted in said tank, means for rotating said shaft, a horizontal frame, 70 grooved bearings for the same at each side of the glue tank, spaced rubber rolls mounted on a pin supported in the forward end of said frame, said rubber rolls being normally in contact with the glue roller and rotated thereby, a push plate attached to said frame 75 below said rubber rolls and projecting beyond them, means for giving said frame a forward and backward movement whereby on the forward movement of the frame, said rubber rolls pass over the under surface of said pads in the second branch of said bracket and apply a coating of glue thereto, means for giving said vertical shaft 80 an up and down movement, whereby upon the downward movement of the shaft a coating of glue is applied upon the surface of the covers by such coated pads, while the covers previously so coated are pushed by said push plate to position below and in alignment with said pads in the other branch of the bracket which press the cut-off lengths of paper or like material upon the glue-coated surfaces of the covers, and 85 means for pushing the covers so treated on to the delivery belt.

Signed by me this eleventh day of August, one thousand nine hundred and twenty-seven (1927).

CHARLES A. ALEXANDERSON.
